Primary Examiner—Lisa P. Lichtenstein
Attorney, Agent, or Firm—George Pappas[57] **CLAIM**

The ornamental design for an air filter for attachment to a fan grill, as shown and described.

DESCRIPTION

FIG. 1 is a perspective view of the air filter according to the present invention and shown attached to a fan grill;

FIG. 2 is an enlarged front elevation view of the air filter shown in FIG. 1;

FIG. 3 is an enlarged back elevation view of the air filter shown in FIG. 1;

FIG. 4 is an enlarged left side elevation view of the air filter shown in FIG. 1, the right side elevation view being a mirror image thereof;

FIG. 5 is an enlarged bottom plan view of the air filter shown in FIG. 1; and,

FIG. 6 is an enlarged top plan view of the air filter shown in FIG. 1.

The broken line showing of a fan grill in FIG. 1 is for illustrative purposes only and forms no part of the claimed design.
